US00D648243S

(12) **United States Design Patent**
Schweiger

(10) **Patent No.:** **US D648,243 S**
(45) **Date of Patent:** **** Nov. 8, 2011**

(54) **STONE**

(75) Inventor: **Christoph Schweiger**, Vomp (AT)

(73) Assignee: **Swarovski Aktiengesellschaft**, Triesen (LI)

(**) Term: **14 Years**

(21) Appl. No.: **29/378,413**

(22) Filed: **Nov. 4, 2010**

(30) **Foreign Application Priority Data**

Jul. 19, 2010 (EM) 1225502-0009

(51) **LOC (9) Cl.** **11-01**

(52) **U.S. Cl.** **D11/89**

(58) **Field of Classification Search** D11/1-2, D11/26-29, 89-92; 63/26-28, 32

See application file for complete search history.
